UNITED STATES PATENT OFFICE.

ROBERT G. WAGNER AND ERNEST J. SCHWEITZER, OF LOS ANGELES, CALIFORNIA.

DESIGN FOR A PAN FOR A LIGHTING-FIXTURE.

49,243.

Specification for Design.

Patented June 20, 1916.

Application filed April 12, 1916. Serial No. 90,788. Term of patent $3\frac{1}{2}$ years.

To all whom it may concern:

Be it known that we, ROBERT G. WAGNER and ERNEST J. SCHWEITZER, citizens of the United States, residing at Los Angeles, in the county of Los Angeles and State of California, have invented a new, original, and ornamental Design for a Pan for a Lighting-Fixture, of which the following is a specification, reference being had to the accompanying drawing, forming part thereof.

The figure is a side elevation of the pan.

We claim:

The ornamental design for a pan for a lighting fixture as shown.

In witness that we claim the foregoing, we have hereunto subscribed our names this 5th day of April, 1916.

ROBERT G. WAGNER.

ERNEST J. SCHWEITZER.

Witnesses:

H. G. POLHILL,

B. SAMETH.
